UNITED STATES PATENT OFFICE.

JÜRGEN CALSEN, OF ELBERFELD, GERMANY, ASSIGNOR TO FARBENFABRIKEN VORM.
FRIEDR. BAYER & CO., OF ELBERFELD, GERMANY, A CORPORATION OF GERMANY.

SANTALOL ETHER.

No. 13,008. Specification of Reissued Letters Patent. Reissued Aug. 17, 1909.

Original No. 909,541, dated January 12, 1909, Serial No. 418,958. Application for reissue filed April 13, 1909.
Serial No. 489,743.

To all whom it may concern:

Be it known that I, JÜRGEN CALSEN, doctor of philosophy, chemist, citizen of the German Empire, residing at Elberfeld, Germany, Kingdom of Prussia, have invented new and useful Improvements in Santalol Ether, of which the following is a specification.

My invention relates to the production of new pharmaceutical products, which are chemically ethers of santalol from oil of santal and which according to my researches possess valuable therapeutic properties, being useful substitutes for santalol without the intense and disagreeable taste and the irritating symptoms caused by this compound. They are especially qualified for the treatment of gonorrhea, cystitis, etc., an average dose being between from 0.2 to 0.5 20 grams.

The process for producing the new compounds consists in treating santalylchlorid with sodium alcoholates, such as sodium methylate, sodium ethylate, sodium phenolate, the sodium compound of menthol, etc. or by alkylating santalol. The new products thus produced are limpid liquids which are soluble in alcohol and ether and are insoluble in water. They give with concentrated sulfuric acid a reddish-brown color. On heating santalol-ethers with hydriodic acid, santalyliodid and the corresponding alkyliodids are formed, but since santalyliodid is quickly decomposed, splitting off hydriodic acid, the hydrocarbon santalene is the final product of the reaction.

In carrying out my process practically I can proceed as follows, the parts being by weight: 215 parts of finely powdered phosphorus pentachlorid, contained in a flask, are covered with ligroin and to this a solution of 220 parts of santalol dissolved in 220-250 parts of ligroin is added through a dropping funnel, the flask being cooled and shaken. The reaction begins at once. When the evolution of hydrochloric acid gas has ceased, the undissolved phosphorus pentachlorid is filtered off and the filtrate is washed until it shows a neutral reaction. The ligroin is then driven off and the residue is distilled *in vacuo*. The portion distilling from 162-167° under a pressure of 15 mm. is the santalylchlorid. 250 parts of santalylchlorid are boiled in a vessel con-

nected with a reflux condenser for 72 hours 55 with a solution of 30 parts of sodium in methyl alcohol. The methyl alcohol is distilled off, the residue is dissolved in ether, the ethereal solution is washed with water containing a small quantity of an acid and 60 then with water until it no longer shows an acid reaction. The ethereal solution is then dried over anhydrous sulfate of sodium, the ether is driven off and the residue is distilled *in vacuo*. The new methyl ether of 65 santalol thus obtained is a limpid oil which boils at 149-156° centigrade under a pressure of about 16 mm. It is easily soluble in alcohol, benzene, chloroform and ether and is insoluble in water. The new compound 70 gives with concentrated sulfuric acid a reddish-brown color. It is decomposed by heating it with hydriodic acid, santalyl iodid and methyliodid being obtained. Santalyl-iodid however splits off hydriodic acid 75 again, and is quickly converted into santalene. The formation of the new methyl-ether of santalol takes places probably according to the following formula:

The process is carried out in an analogous manner by using other sodium alcoholates. The ethyl ether of santalol is a limpid oil boiling at 169-175° centigrade under 85 a pressure of about 22 mm. and has the formula:

The phenyl ether of santalol obtainable 90 from santalylchlorid and sodium phenolate is a limpid oil boiling at 232-241° centigrade under a pressure of about 20 mm. and has the formula:

The menthyl ether of santalol obtainable 95 from santalylchlorid and the sodium compound of menthol is a limpid oil boiling at 201-210° centigrade under a pressure of about 5 millimeters and has the formula:

Having now described my invention and in what manner the same is to be performed, what I claim as new, and desire to secure by 105 Letters Patent is:

1. The herein-described new ethers of santalol, obtainable by reacting santalyl

- chlorid with sodium alcoholates, which are 5 limpid liquids soluble in ether and in alcohol, insoluble in water and giving with concentrated sulfuric acid a reddish-brown color, forming on heating with hydriodic acid santalyliodid, which, however, is quickly 10 decomposed into santalene; and exhibiting valuable therapeutic properties, substantially as hereinbefore described.
10. 2. The herein-described new methyl-ether of santalol, being a valuable remedy, obtainable by the action of sodium methylate upon santaly-chlorid, which is a limpid 15 colorless oil being almost tasteless; boiling at 149-156° centigrade under a pressure of

about 16 mm., soluble in alcohol and ether, insoluble in water, and giving with concentrated sulfuric acid a reddish brown color and being decomposed by heating with hydriodic acid into santalyl iodid and methyl iodid, santalene being finally formed from santalyl-iodid, substantially as hereinbefore described.

In testimony whereof I have hereunto set my hand in the presence of two subscribing 25 witnesses.

JÜRGEN CALLSEN. [L.S.]
